ELECTRICAL CONDENSER

Joseph A. Flanzer, Laurelton, Long Island, N. Y.,
assignor to Electro-Motive Manufacturing Co.,
Inc., New York, N. Y., a corporation of New
York

Application August 13, 1936, Serial No. 95,751

9 Claims. (CL 175—41.5)

This invention relates to electrical condensers, and more particularly to small fixed-adjustable "padder" condensers commonly employed in radio receivers.

5 There are many uses for small fixed-adjustable condensers, an important one being for use as a padder condenser in radio receivers of the superheterodyne type. Such a condenser is connected in series with the oscillator of the superheterodyne to help obtain the desired frequency difference between the oscillator circuit and the input circuit of the receiver in order to produce a desired intermediate frequency. These condensers have ordinarily been made with an insulation base or case against which the bottom plate of a group of bent condenser plates would rest, the capacitance being adjusted by a screw operating to compress the plates together to desired amount. Considerable difficulty has arisen 10 by reason of undesired changes in capacitance of the condenser after it has been set to desired value. I have found that shrinkage or warping or deformation of the insulation, due to ageing or insufficient curing or the effects of high relative humidity, or any of numerous other factors which lead to slight change in dimension or shape, results in a change of capacitance which, in a superheterodyne receiver for example, may throw the intermediate frequency entirely out of 15 range and so make the receiver nearly or wholly inoperative.

With poorly cured synthetic resinous material, I have found that changes of the order of 30% may result at the elevated temperature which is 20 found in the chassis of a radio set. This difficulty, caused by shrinkage or deformation of the insulation, arises not only when using the synthetic resin or condensation product with a filler such as wood flour but even when using a much more expensive filler such as mica.

40 The primary object of the present invention is to overcome the foregoing difficulties, and to this end the insulation case is employed solely to prevent relative rotation or lateral movement 45 of the plates. The lowermost of the group of plates does not rest on the insulation case, but instead rests either directly or through a rigid metallic washer upon the end of an internally threaded bushing which itself receives the adjusting screw. With this arrangement the adjustment is determined solely by metallic parts (except for the thin mica dielectric between the condenser plates, which, however, does not shrink or flow), and the adjustment is wholly independent of the molded insulation case. The wall of

the metallic bushing passing through the case is made of sufficient thickness to take the load of the condenser adjusting screw, without depending upon support from the molded insulation. Shrinkage or warping or deformation of the insulation therefore has no effect whatsoever on the critical spacing of the condenser plates and the capacitance of the condenser. In fact, with my improved construction the mechanical nature of the insulation material employed is rendered relatively unimportant, and while the material should be a reasonably good dielectric, it need not have extreme mechanical perfection. For example, a mixture of synthetic resin or condensation product with wood flour 15 may be employed with entire satisfaction.

Other objects of my invention center about the shaping and mounting of the plates, and are to so design the plates that all may be made exactly alike and may be completely formed in a single die; to so support the plates in the case that variation or manufacturing tolerance in the manufacture of the case will not result in displacing the superposed plates from their desired concentric relation; and to obtain a desired spacing 20 between the plates, with a minimum curvature of the individual plates. With these objects in view, the plates are supported by upper and lower tongues at diagonally opposite corners of the plates, these tongues being received in slots 25 cut through the side walls of the case. The plates are all alike and are curved or warped slightly during manufacture. Alternate plates are turned in opposite direction, this producing a desired spacing between the plates, with a minimum curvature of the individual plates. The manufacture thus stays well within the elastic limit of the material, and there is no danger of the material failing to spring back to curved 30 position when the adjusting screw is tightened and then released. Variations in the location of the slots cut through the side walls of the case may produce a slight oscillation of the plates but does not displace the center holes from concentricity with one another and the bushing. It is for this reason that the tongues are preferably located at diagonally opposite 35 corners.

Still another object of the invention is to avoid the necessity for forming the thin sheets of mica dielectric with locating lugs or the like. Because of the provision of walls on all sides of the case, the mica may be given a plain rectangular or, even more preferably, square outline and is accurately located in place by the side 40 45 50 55

walls of the case. Moreover, the edges of the mica sheets are protected by the side walls of the case. A still further object of my invention is to provide a simplified construction including 5 the use of rigid cupped washers for effectively compressing a stack of condenser plates and for elevating the same from the bottom of the insulation case, while minimizing the capacitance to ground when the condenser is not grounded. 10 Still another object is to provide convenient soldering lugs which are riveted or eyeleted together to make possible convenient testing of the capacitance of the unit before actually soldering the same in a radio set.

15 To the accomplishment of the foregoing and other objects which will hereinafter appear, my invention consists in the electrical condenser elements and their relation one to the other, as hereinafter are more particularly described in the specification and sought to be defined in the 20 claims. The specification is accompanied by a drawing in which:

Fig. 1 is a section taken in elevation through a paddar condenser embodying features of my invention; 25

Fig. 2 is a section taken in the plane of the line 2—2 of Fig. 1;

Fig. 3 is a section looking in plan in the plane of the line 3—3 of Fig. 1;

30 Fig. 4 shows the insulation case in perspective;

Fig. 5 illustrates one of the metallic condenser plates;

Fig. 6 is a section showing a modification;

Fig. 7 schematically represents the plate arrangement of a modified condenser having an odd 35 number of plates and one side of which is grounded; and

Fig. 8 schematically represents the plate arrangement of a condenser having an even number 40 of plates and one side of which is grounded.

45 Referring to the drawing and more particularly to Figs. 1 through 5 thereof, the fixed-adjustable condenser there illustrated is a paddar condenser for use in radio receivers of the superheterodyne type. It will be understood that such condensers are relatively tiny in dimension, the drawing being approximately three times full size. The condenser comprises an internally threaded metallic bushing 12 which receives the adjusting screw 14 of the condenser. The particular condenser here illustrated has an odd number of 50 metallic plates and is of the ungrounded type, that is, the top and bottom plates are insulated from bushing 12 and adjusting screw 14 by large 55 thin mica washers 16. Additional sheets 18 of mica dielectric are disposed between the successive condenser plates. The first, third, and fifth condenser plates are numbered 20, while the second and fourth condenser plates, which form the 60 other side of the condenser, are numbered 22. These condenser plates are warped somewhat in order to initially space the same apart, the capacitance of the condenser being increased by 65 tightening adjusting screw 14 which operates to compress and flatten the condenser plates into close engagement with one another.

The condenser plates are located by a molded insulation case C having an end wall 24 mounted on one end of bushing 12 and having side walls 26 70 on all four sides. In accordance with the present invention, the stack of condenser plates does not rest upon or even bear against the bottom or end 75 24 of the case. Instead the assembly of condenser plates rests upon a rigid metallic washer 28 which in turn rests directly upon the outwardly flanged

or riveted inner end 30 of bushing 12. Because of this arrangement of metal on metal, the load of the adjustment screw 14 is applied directly to bushing 12 and is wholly independent of the molded insulation case C. The wall 32 of bushing 12, which passes through the insulation case, is made heavy enough to itself take the force applied by adjusting screw 14, and the molded material at the center of the case immediately surrounding the bushing does not assist in supporting the inner end of the bushing. Consequently, shrinkage or other change in dimension of the case in no way affects the adjustment of the condenser.

The bottom or end 24 of the case is preferably 15 recessed, as is indicated at 34, to receive and partially embed the metallic thrust washer 28. However, it will be understood and should be evident from the drawing, that although the washer is partially embedded in the insulation, 20 it protrudes far enough to hold the stack of condenser plates elevated above the bottom of the case. It will also be noted that the rigid metallic thrust washer 28 is cupped or dished somewhat, it being convex downwardly. This is of advantage in order to insure obtaining the effect of the perfectly flat washer when adjusting screw 14 is tightened, that is, the washer is made somewhat concave toward the condenser plates, in order to make certain that it is not somewhat 30 convex toward the condenser plates. Moreover, this arrangement is of advantage when, as is here the case, the condenser is insulated from ground, for the capacitance to ground is minimized by reason of the fact that the washer 28 contacts 35 with the mica washer 16 at only the peripheral edge of washer 28, instead of contacting over the entire flat surface of the washer.

A rigid metallic thrust washer 36 is also employed at the top of the condenser, beneath the 40 head of adjusting screw 14. This washer may be similar to washer 28 and is preferably cupped or dished somewhat for similar reasons. This washer provides a large area of pressure which serves to fully flatten the condenser plates for 45 maximum capacitance when the adjusting screw is tightened. It will be seen that the assembly of condenser plates is supported between metallic washers 28 and 36, and that the pressure between the metallic washers is determined directly by 50 the engagement of adjusting screw 14 in bushing 12, for the screw head bears on washer 36, while the bushing bears on washer 28. The insulation case C plays no part in the adjustment of the 55 condenser.

The condenser plates are all alike and may be formed in a single die. The configuration of the individual plates is best shown in Fig. 5 in which it will be seen that the plate comprises a rectangular or preferably square area 40, with an 60 oversized central hole 42. A locating tongue 44, stepped at 46, projects from one side of the condenser plate, while a locating tongue 48, stepped at 50, projects from the opposite side of the condenser plate. The tongue 48 is elongated and 65 acts as a soldering lug. The plate is given a slight curvature during manufacture, and all of the plates may be shaped and curved alike.

The side walls 26 of case C are cut away to form 70 locating slots 52, best shown in Fig. 4. The condenser plates are laid in case C, with the tongues 44 and 48 received in two of the slots 52. Alternate plates are faced in opposite direction, the tongues 44 and 48 being received in the other two 75 of the four slots. Thus, referring to Fig. 3, the 80

plates 20 have soldering lug 48 disposed at the upper left-hand corner of the case, while the plates 22 are disposed with the soldering lugs at the lower left-hand corner of the case. The soldering lugs of the odd plates are thus brought into superposition, and similarly the soldering lugs of the even plates are brought into superposition. At the same time, the plates are spaced apart by reason of the opposite curvature of the successive plates. It will be understood that the tongue 44 may, if desired, be located at the same side of the plate as soldering lug 48, but the present arrangement is considered preferable, among other things because any variation or tolerance in the location of slots 52 tends to merely oscillate the condenser plates about their center, rather than to displace or shift the same laterally away from concentricity.

The sheets 18 of mica dielectric need not be provided with locating tongues or projections, and this is of advantage because of the difficulty of working the mica and the increased expense when given a special shape. The sheets of mica are simply square and are accurately received within the side walls 26 of the case. The side walls thus accurately locate the mica sheets in proper position and protect the edges of the same against splitting and damage such as frequently result when these edges are exposed. The top and bottom pieces of mica, numbered 16, may be circular washers instead of square pieces, the circular form being standardized and even more inexpensive than the square form. These washers may be given a diameter equal to the internal dimension of the case, as is clearly shown in Fig. 3, thus holding the washers in proper location. It will be noted that mica washers 16 are larger in diameter than metal washers 36, and that the square sheets of mica 18 between the plates are larger than the center or square portion of the metal plates. Similarly, the center holes in the mica are smaller than the holes in the metal plates.

It has heretofore been the practice to bend the soldering lugs upwardly toward the rear of the condenser, the lugs being left in superposed relation, but without securing the same together. This has proved inconvenient when testing the capacitance of the unit, and such tests are made not only by the condenser manufacturer but also by the manufacturer of the radioreceiver in which the condenser is to be used. To obtain contact with all of the plates, it has been necessary to clamp the lugs together in a special fixture, for otherwise a correct reading cannot be obtained. In accordance with the present invention, the soldering lugs are left flat, and round holes 54 punched therethrough thus come into true superposition. The lugs are riveted together, either by solid rivets or, more preferably, by eyelets 56 shown in Figs. 1 and 3. The lugs may also be soldered, but I find that the mechanical connection obtained by riveting the same together is adequate for good electrical connection. Where a solid rivet is used, a lead or pigtail may be placed beneath the head of the rivet, whereas with eyelets, as shown in Fig. 3, it is contemplated that the leads to the condenser be slipped through the eyelet and soldered in place. With this riveted arrangement the capacitance may be tested by merely touching the terminals against a suitable contact device, it being unnecessary to provide special clamps for the soldering lugs. At the same time, the soldering operation is made

more convenient when the condenser is placed in a radio set or the like, for the lead wire may be soldered to only one point, and it is not necessary to worry about obtaining a successful soldered connection to each of the numerous condenser plates. (While only five plates are shown in the drawing, it is not uncommon to employ as many as thirteen plates.) Heretofore after completion of the soldering operation, it was sometimes found that one or more of a group of plates has been insulated by the soldering flux, or, for some other reason, has not been properly soldered to the main group of plates. The fault is not discovered until the radio receiver is finally tested, and even when the defective set has been found, it is exceedingly difficult to locate the exact source of trouble. In some cases, contact with the lead is made but is poor, in which case the radio receiver may be operative but noisy, and this trouble is also a difficult one to locate. None of these problems arises when, as is here the case, the soldering lugs are riveted together.

It is not essential to employ a bottom washer 28 which is separate from the bushing of the condenser. Thus, referring to Fig. 6, I show a bushing 60 the inner end of which is enlarged to form a flange or plate 62 which replaces the bottom washer 28 heretofore described. In this case the bushing is applied to the end wall 64 of the insulation case by means of a nut 66 threaded on the outside of the bushing. A second nut, corresponding to the nut 68 shown in Figs. 1 and 2, is, of course, employed to mount the condenser in place. The remaining details of the condenser need not be described and may be like those heretofore described. In the claims, in referring to a washer, I mean to include an integral flange, as in this Fig. 6, as well as a separate washer, as in Fig. 1.

In the condenser of Fig. 1, both sides or both sets of plates are insulated from ground. In many cases this precaution is not necessary, and one side of the condenser may be grounded. In such case it is preferable to employ an odd number of plates, for then the top and bottom plates may bear directly against the top and bottom washers. This arrangement is schematically indicated in Fig. 7 in which it will be seen that the odd plates 70 are grounded, for the top and bottom plates bear directly against the top and bottom washers 72 and 74. It is somewhat preferable to make the odd plates convex upwardly, for then the locating tongues 44 and 48 remain well within the locating slots 52 even when a large number of condenser plates are used. The odd plates 70 are, of course, insulated from the even plates 76 by sheets of mica 78. No mica washers are employed, however, beneath the bottom plate and above the top plate.

The requirements of capacitance range may necessitate the use of an even number of plates while dealing with a condenser in which one set of plates may be grounded. The plate arrangement of such a condenser is schematically illustrated in Fig. 8, in which the odd plates 80 are insulated from bottom washer 82 by means of a mica washer 84. The even plates 86 are grounded by direct contact to the top washer 88. The odd and even plates are, of course, separated from one another by mica dielectric 90.

It is believed that the construction and operation, as well as the many advantages of my improved fixed-adjustable condenser will be apparent from the foregoing detailed description. It will also be apparent that while I have shown

and described my invention in preferred forms, many changes and modifications may be made in the structures disclosed, without departing from the spirit of the invention, defined in the following claims. In certain claims, I have, for convenience, referred to the plates as positive and negative, but it will be understood that these terms are used in only a relative or instantaneous sense for the condenser is used in a high-frequency alternating current circuit.

I claim:

1. A small fixed-adjustable condenser comprising a metallic bushing which is externally threaded to receive a nut for mounting the condenser in place, and which is internally threaded to receive an adjusting screw, an insulation member mounted around the bushing, a rigid metallic washer disposed at the inner end of the bushing, a plurality of condenser plates over said washer, said washer operating to keep said plates away from said member, said insulation member being provided with means to support the plates against relative lateral movement, thin sheets of mica dielectric disposed between said plates, said plates being so relatively bent as to normally space the same apart, and an adjusting screw passing through said plates and threadedly received in said bushing for compressing the plates together and thereby determining the capacitance of the condenser, the arrangement being such that the adjustment is determined solely by metallic and mica parts and is independent of the insulation member.

2. A small fixed-adjustable condenser comprising a metallic bushing which is externally threaded to receive a nut for mounting the condenser in place, and which is internally threaded to receive an adjusting screw, a molded insulation case mounted around the bushing, a rigid metallic washer disposed within said case at the inner end of the bushing, a plurality of condenser plates in said case over said washer, said washer supporting said plates above the subjacent wall of the case, said case being open at the top but provided with side walls which support the plates against relative lateral movement, thin sheets of mica dielectric disposed between said plates, said plates being so relatively bent as to normally space the same apart, a rigid metallic washer above said plates, and an adjusting screw passing through said plates and threadedly received in said bushing for compressing the plates together and thereby determining the capacitance of the condenser, the arrangement being such that the adjustment is determined solely by metallic and mica parts and is independent of the molded insulation case.

3. A small fixed-adjustable condenser comprising an internally threaded metallic bushing, a molded insulation case having an end wall mounted on said bushing and having side walls, said side walls being cut away to form locating slots, condenser plates and mica dielectric plates disposed in said case and bearing against the inner end of said bushing and being supported thereby in such manner as not to bear against the end wall of the case, said condenser plates having tongues projecting therefrom and so dimensioned and located as to be received in the aforesaid slots, said plates being bent during manufacture and being thereby spaced apart, said mica dielectric plates having a simple rectangular configuration devoid of locating tongues and dimensioned to be received within and located by the side walls of the case, and an adjusting screw passing

through said plates and bushing for compressing the plates to desired capacitance, the adjustment depending solely upon the relation of the metallic plates and mica dielectric and being independent of the molded insulation case.

4. A small fixed-adjustable condenser comprising an internally threaded metallic bushing, a molded insulation case having an end wall mounted on said bushing and having four side walls, said side walls being cut away to form four locating slots, condenser plates and mica dielectric plates disposed in said case and bearing against the inner end of said bushing and being supported thereby in such manner as not to bear against the end wall of the case, said condenser plates being identical in construction and having tongues projecting therefrom, said tongues being so dimensioned and located as to be received in the aforesaid slots, alternate plates being turned one way to be received in two of the slots, and the other plates being turned the other way to be received in the other two slots, said plates being similarly bent during manufacture and being thereby spaced apart when alternate plates are turned to opposite position as aforesaid, and an adjusting screw passing through said plates and bushing for compressing the plates to desired capacitance, the adjustment depending solely upon the relation of the metallic plates and mica dielectric and being independent of the molded insulation case.

5. A small fixed-adjustable condenser comprising an internally threaded metallic bushing, a molded insulation case having an end wall mounted on said bushing and having four side walls, said side walls being cut away to form four locating slots near the corners of the case, condenser plates and mica dielectric plates disposed in said case and bearing against the inner end of said bushing and being supported thereby in such manner as not to bear against the end wall of the case, said condenser plates being identical in construction and having tongues projecting at diagonally opposite corners thereof, said tongues being so dimensioned and located as to be received in the aforesaid slots, alternate plates being turned one way to be received in two diagonally opposite slots, and the other plates being turned the other way to be received in the outer two diagonally opposite slots, said plates being similarly bent during manufacture and being thereby spaced apart when alternate plates are turned to opposite position as aforesaid, said mica dielectric plates having a simple rectangular configuration devoid of locating tongues and dimensioned to be received within and located by the side walls of the case, and an adjusting screw passing through said plates and bushing for compressing the plates to desired capacitance, the adjustment depending solely upon the relation of the metallic plates and mica dielectric and being independent of the molded insulation case.

6. A small fixed-adjustable condenser comprising a metallic bushing which is internally threaded to receive an adjusting screw, an insulation member mounted around the bushing, a rigid metallic plate disposed at one end of the bushing, a condenser plate over said first plate, said first plate operating to keep said condenser plate away from said member, said insulation member being provided with means to support the plates against relative lateral movement, a thin sheet of mica dielectric disposed between said plates, said plates being so relatively bent as to normally space the same apart, and an adjusting screw passing through said plates and threadedly received in

5 said bushing for compressing the plates together and thereby determining the capacitance of the condenser, the arrangement being such that the adjustment is determined solely by metallic and mica parts and is independent of the insulation member.

10 7. A small fixed-adjustable condenser comprising a metallic bushing which is internally threaded to receive an adjusting screw, an insulation member mounted around the bushing, a rigid metallic plate disposed at one end of the bushing, a condenser plate over said first plate, said first plate operating to keep said condenser plate away from said insulation member, said insulation member being provided with means to support the plates against relative lateral movement, a thin sheet of mica dielectric disposed between said plates, and an adjusting screw passing through said plates and threadedly received in said bushing for compressing the plates together, the arrangement being such that the adjustment is independent of warping of the insulation member.

15 8. A small fixed-adjustable condenser comprising a metallic bushing which is internally threaded to receive an adjusting screw, an insulation member mounted around the bushing, a first condenser plate disposed at one end of the bushing, means at the end of the bushing operating to keep said condenser plate away from said insulation member, a second condenser plate over said first plate, said insulation member being provided with means to support the plates against relative lateral movement, a thin sheet of mica dielectric disposed between said condenser plates, 20 said plates being so relatively bent as to normally space the same apart, and an adjusting screw passing through said plates and threadedly received in said bushing for compressing the plates together and thereby determining the capacitance of the condenser, said adjusting screw functioning to compress the plates together between the head of the screw and the end of the bushing, whereby the capacitance of the condenser is determined by compressing the plates between 25 metal parts and without compression of the aforesaid insulation member, so that the adjustment of the condenser is independent of shrinkage and cold flow of the insulation member.

25 said plates being so relatively bent as to normally space the same apart, and an adjusting screw passing through said plates and threadedly received in said bushing for compressing the plates together and thereby determining the capacitance 5 of the condenser, the arrangement being such that the adjustment is independent of warping of the insulation member.

30 9. A small fixed-adjustable condenser comprising a metallic bushing which is internally threaded to receive an adjusting screw, an insulation member mounted around the bushing, a first condenser plate disposed at one end of the bushing, means at the end of the bushing operating to keep said condenser plate away from said insulation member, a second condenser plate over said first plate, said insulation member being provided with means to support the plates against relative lateral movement, a thin sheet of mica dielectric disposed between said condenser plates, 20 said plates being so relatively bent as to normally space the same apart, and an adjusting screw passing through said plates and threadedly received in said bushing for compressing the plates together and thereby determining the capacitance of the condenser, said adjusting screw functioning to compress the plates together between the head of the screw and the end of the bushing, whereby the capacitance of the condenser is determined by compressing the plates between 30 metal parts and without compression of the aforesaid insulation member, so that the adjustment of the condenser is independent of shrinkage and cold flow of the insulation member.

JOSEPH A. FLANZER. 35
